UNITED STATES PATENT OFFICE.

DAVID E. GRAY, OF HIGHLAND PARK, ILLINOIS.

MECHANISM FOR WINDING FILMS.

1,327,034.

Specification of Letters Patent.

Patented Jan. 6, 1920.

Application filed November 26, 1915. Serial No. 63,370.

To all whom it may concern:

Be it known that I, DAVID E. GRAY, a citizen of the United States, residing at Highland Park, in the county of Lake and State of Illinois, have invented certain new and useful Improvements in Mechanism for Winding Films, of which the following is a specification.

My invention relates to an improved mechanism for winding film such as is used in connection with the moving picture art, the object of the invention being to provide a winding mechanism that will receive the film from the projecting apparatus and wind it so that it may be used again without an intermediate rewinding operation.

By my invention the film is fed through the projecting mechanism in substantially the usual manner and when delivered from the projecting mechanism is fed into a hollow drum so that the film is built up inside of the drum into a coil of constantly decreasing inner diameter, the outer diameter of the coil, which is the diameter of the first turn, being constant. My invention is characterized by feeding the film into the inside of the drum instead of rotating the drum and pulling the film into it, for I find that by feeding the film into the drum a uniform and compact coil is produced, which is difficult if not impossible to secure by driving the drum and thus pulling the film into the drum.

My invention also consists in the particular art of winding film referred to above, that is to say, feeding the film into a container so that the outermost convolution is formed first, and then the subsequent convolutions are formed inside of the first convolution, the feeding operation serving not only to feed the film into the coil thus formed, but also to rotate the coil and container as the film is fed into the same.

My invention also includes mechanism for accomplishing the results referred to, as will be more fully understood by reference to the accompanying drawings showing one embodiment of my invention.

Figure 1 is a side elevation of a moving picture projecting machine having my improved film winding mechanism attached thereto.

Fig. 2 is a top view of the parts shown in Fig. 1, the magazine or supply roll container being removed for the sake of clearness.

Fig. 3 shows in an enlarged view similar to Fig. 1 the framework and mechanism carried thereby for feeding the film into the receiving drum, the latter being removed 60 for the sake of clearness, and the lay-block supporting the film chute and feeding mechanism being shown in section back of said chute.

Fig. 4 is a view taken from the right 65 hand of the parts shown in Fig. 3.

Fig. 5 is a detail view of the mechanism employed to prevent back rotation of the film feeding mechanism shown in Fig. 3.

Fig. 6 is a horizontal sectional view 70 through the parts shown in Fig. 1 taken along the line 6—6, the film receiving drum being shown in horizontal central section to more clearly disclose the film feeding device.

Fig. 7 is a detail side view of the chute, feeding roller and stripping roller employed to feed the film into the receiving drum.

Fig. 8 is a side view of the receiving drum 80 and its supporting bracket removed from the rest of the machine.

Fig. 9 is a vertical sectional view through the parts shown in Fig. 8 taken along the line 9—9, with the addition of one guard 85 roll.

Fig. 10 is a detail view of the hinged connection between the parts of the receiving drum.

Fig. 11 is a detail view of the locking 90 mechanism employed to hold the parts of the receiving drum together.

Fig. 12 is a vertical sectional view of the parts shown in Fig. 11 taken along the line 12—12.

Fig. 13 is a diagrammatic view showing the supply and receiving rolls of film, taken from the opposite side to that shown in Fig. 1, and in this figure the course of the film from the supply roll to the receiving 100 roll is traced diagrammatically.

Similar numerals refer to similar parts throughout the several views.

As shown in Fig. 1, a lantern 20 is supported by a suitable tripod mechanism 21 105 so that it may be moved into line with the film driving mechanism 22 or out of line therewith as desired, so that the film may be threaded through the driving mechanism. Since the lantern and the driving mechanism do not themselves constitute my present invention, and since these parts may be

of any type common in the art of moving picture projection, but brief reference to the mechanism is required. The driving mechanism consists essentially of the driving sprockets 23 and 24 geared together as indicated so they may be operated by the crank 25. The film 26 is led through the choke rolls 27 to the driving sprocket 24, and upon leaving this sprocket forms the 10 loop 28 extending through the guide mechanism 29 in line with the lantern 20. From the guide mechanism the film is led around the kicker 30 to the driving sprocket 23 from which it is delivered and passes to the 15 choke rolls 31 supported by the bracket 32 from the framework 33 of the film receiving mechanism.

The framework 33 is supported from the bottom of the upper framework 34 used to 20 support the supply roll or magazine 35 and the framework 34 together with the parts carried thereby, which include all of the mechanism relating to the supply and receiving rolls, may be secured to the gear casting 22 or removed therefrom by the operation of the clamping screw 36. One of the 25 objects of my invention is to provide an improved type of film winding mechanism of the class described which may readily be applied to existing types of projecting apparatus, whether by means of the connections described or by other means of connection depending upon the type of the projecting apparatus.

30 The film receiving mechanism consists of 35 a hollow drum 37 supported as indicated in Fig. 9 by arms 38 upon a bolt 39 which serves to clamp the inner members of ball 40 races against a sleeve 40. The outer members of the ball races and a spacing sleeve 41, which have an over all length slightly less than that of the inner ball races and sleeve 40, are rigidly secured in a hub 42 mounted at the lower end of arms 43 secured at their 45 upper ends to the plate 44. The rim of the drum 37 is formed in two parts hinged together at 45 and provided at their other ends with a locking bolt 46, which as seen in Figs. 11 and 12, is flattened and engaged 50 by a transverse operating rod 47 extending through a slot 48 in one of the ears 49 projecting from the end of the lower member of the drum to receive the bolt 46. The upper member of the drum is provided with a central ear 50 for receiving the bolt 46, and this ear 50 is provided with a slot through its side wall as indicated in Fig. 12, which slot is of just sufficient width to permit the bolt 46 to pass through it when said bolt is 55 turned by the rod 47 to a position bringing its smallest dimension in line with said slot. The upper end of the lower member of the drum is recessed as indicated at 51 and provided with a small cover plate 52 on the 60 inner surface of said member so that the slot 65

formed between said plate and the end of the lower member may receive the end of the film first fed into the drum. The inner surface of the lower end of the upper member of the drum is slightly cut away as indicated at 53 so that the second convolution of the film into the drum will form a true circle therein without a bulge over the end of the film. 70

The two lower arms 38 shown in Fig. 8 are not secured to the lower member of the drum, but merely serve to steady said member in place so that the latter may be freely opened when the locking bolt 46 is rotated.

The arms 38 have secured to them a brake 80 ring 54 against which a spring plunger 55 carried by the arms 43 rests. The pressure exerted by the spring plunger may be changed as desired by the adjusting screw 56.

The edge of the plate 44 is provided with 85 projecting lugs 57 which extend under the lugs 58 carried by the top plate of the framework 33, and a further means for properly adjusting the plate 44 in position upon the framework 33 consists in the pins 90 59 and 60 carried by the plate 44, which project downwardly to enter corresponding holes formed in the top plate of the framework 33. The pin 60 is sufficiently long so that when the receiving drum is in place 95 on the framework 33 the pin 60 as shown in Fig. 4 will engage the left hand end of the lever 61 pivotally mounted at 62 from the underside of the top plate of the framework 33. 100

The framework 33 consists of the side members 33^a projecting downwardly from the top plate of said framework, which side members are connected together by the bottom member 33^b, and these members together support the guide rods 63 upon which the lay-block 64 is mounted so as to be freely movable in a vertical direction. The upper portion of the framework carries a shaft 65 to which a grooved pulley 66 is rigidly secured, which shaft has secured near its other end a disk 67. The shaft also carries a second grooved pulley 68, which is rotatably mounted thereon, being held firmly in engagement with the disk 67 by a spring 69 and thumb nut 70, which nut may be turned upon the shaft to change the tension of the spring 69 as desired, so that any desired degree of pressure may be exerted between the pulley 68 and the disk 67. As indicated 110 in Figs. 1 and 2 the pulley 68 is connected by a crossed belt 71 with a similar pulley 115 carried by the shaft to which the crank 25 is secured. 120

The lay-block 64 carries a bearing for a 12 shaft 72 rotatably mounted therein and extending horizontally at an angle of substantially 60 degrees to the plane of the guide rods 63. The inner end of this shaft 72 has rigidly secured to it a grooved pulley 73 and 13

the outer end of this shaft has rigidly secured to it the feeding sprocket 74 by which the film is fed into the hollow drum 37. The lay-block 64 also serves to support a stud 75 extending outwardly therefrom in horizontal position to rotatively support a guiding roll 76 around which the film is led from the choke rolls 31. From the guide roll 76 the film is led around a spiral directing chute 10 which partially surrounds the shaft 72 and the feeding sprocket 74, this chute being supported by the lay-block 64. The end of the chute 76 terminates as indicated in Fig. 7 close to the left hand side of the sprocket 74 and in this manner the film is led to the feeding sprocket 74 so that it may be properly engaged and operated by the latter. The inner portion of the chute 76 has pivotally secured thereto at 77 an arm 78, the lower end of which has rigidly secured thereto the shaft 79, which rotatably supports at its ends the stripping rollers 80, which are of such a length as to just engage the edges of the film and prevent it from hanging to 25 the sprocket 74 as the latter revolves, and in this way the film fed into the hollow drum by the sprocket 74 is held against the inner surface of the preceding convolution and prevented from buckling.

30 The lay-block 64 also carries an upwardly extending bracket 81, which supports, by means of a suitable stud, a grooved idler pulley 82, the hub of which, as indicated in Fig. 5, is provided with ratchet teeth engaged by a pawl 83 to prevent back rotation of the pulley 82. A stop plate 84 is secured by a suitable screw or screws in the manner indicated to the lay-block 64 to keep the pawl 83 in a position to engage the ratchet teeth referred to by gravity. The bracket 81 also has secured to it a boss 85 through which the right hand one of the rods 63, as shown in Fig. 3, extends so that this boss constitutes an additional bearing for the 40 lay-block. The right hand vertical member 33^a of the framework 33 supports by means of a stud a grooved idler pulley 86 near the bottom of the framework 33. The pulleys 82 and 86 are so inclined in vertical planes 45 as indicated in Fig. 6 that the driving belt 87 extending around them and also around the pulley 66 will properly drive the pulley 73, regardless of the vertical position of the lay-block 64. Furthermore, it will be observed that the driving effort exerted by the belt 87 as it passes around the pulleys 73, 82 and 86 is in a downward direction from the vertically movable pulley 82 to the fixed pulley 86, and this results in there always being 50 during the winding operation a downward thrust upon the lay-block 64, which serves to hold the feeding sprocket 74 firmly in engagement with the film wound into the hollow drum 37. If for any reason it is necessary to stop the winding operation as, for

example, on account of breakage of the film and to release the feeding sprocket 74 from the film wound into the hollow drum, this is readily done by turning the crank 25 backward, which at once lifts the lay-block 70 64 and the parts carried thereby away from the film in the hollow drum, since the ratchet carried by the pulley 82 prevents back rotation of this pulley and the upward pull exerted upon the left hand portion of the belt 75 87 as shown in Fig. 3 lifts the lay-block and parts carried thereby.

The purpose of the lever 61 is as follows: When the hollow drum is to be put in place upon the framework 33 it is necessary that 80 the lay-block 64 shall be held in a sufficiently elevated position so that the feeding sprocket 74 and the stripping rollers 80 shall clear the inside of the hollow drum. To accomplish this a bracket 88 is secured to the right 85 hand vertical member 33^a of the framework 33 and a bell crank lever 89 is pivotally mounted upon this bracket at 90. The bell crank lever 89 has an outwardly extending flange 89^a at its lower end, which when the 90 downwardly extending arm of the bell crank lever is in vertical position, rests below the outer end of a rod 91 extending from and rigidly secured to the boss 85 carried by the lay-block. The relation of the parts is 95 such that when the lay-block is supported by the engagement of the rod 91 with the bell crank lever 89 that the feeding sprocket 74 and the stripping rolls 80 clear the inner surface of the hollow drum. The bell crank 100 lever 89 is connected with the right hand end of lever 61 by means of a rod 92, and the horizontally extending end of the bell crank lever is also connected by a second rod 93 with a lever arm 94 pivotally supported at 95 from a bracket 96 secured to the lower portion of the framework 33. The lower end of the rod 93 is provided with a slot 97 which loosely engages a pin 98 carried by a lever 94 so that the lever 94 may 110 move freely relative to the rod 93, and when the pin 98 is in the lower end of the slot 97 the lever 94 is held in horizontal position. The outer end of the lever 94 is bent at an angle to the body portion of said lever as indicated in Fig. 3, so that when the lever is in horizontal position as shown in dotted lines in Fig. 6, which occurs at the same time that the rod 91 is engaged by the bell crank lever 89, the lever 94 serves to 115 support the end portion of the film and hold the film up against the feeding sprocket 74 after the film has been threaded around the guide roller 76 and through the spiral chute 76', after which the hollow drum is put in place upon the framework 33 as above described. When the hollow drum is put in place, however, the pin 60 operates the lever 61 thus removing the bell crank lever 89 from engagement with 120 125 130

the rod 91, which permits the lay-block 64 and members carried thereby to drop, so that the film is brought into engagement with the inner surface of the hollow drum. At the same time the rod 93 quickly moves the lever 94 to vertical position on account of the leverage employed thus releasing the end portion of the film and as it is usual to drop the hollow drum and its supporting frame-work into position after the pins 59 and 60 are entered in the corresponding holes in the top plate of the framework 33, the rod 93 is moved with sufficient rapidity so that the lever 94 is carried upward beyond its vertical position and rests against the framework 33, which extra motion is permitted by the slot 97. The released end of the film is then inserted under the plate 52 by rotating the hollow drum so as to bring the portion of the film between the plate 52 and the feeding sprocket 74 snugly against the inner surface of the hollow drum, for which condition the apparatus is in readiness to be operated by the turning of the crank 25.

It will be understood that the supply roll 35 and the hollow drum are in practice entirely inclosed in fireproof casings which are not shown since they are common in the art, the choke rolls 27 and 31 being provided to stop the film openings in the casings if for any reason the film should get on fire. As a result of the construction it will be observed that the film upon leaving the driving mechanism 22 is fed into the receiving drum 30 and that this drum is rotated entirely by the force exerted upon the film in the drum by the feeding sprocket 74. The spring plunger 55 has such a pressure exerted upon it as to prevent the drum being rotated in advance of the film through uneven resistance of any kind to rotation, and thus the film is caused to build up uniformly on the inside of the drum, each convolution being firmly pressed against the inner surface of the one preceding it and any tendency to buckling of the film being removed by stripping rolls 80. Since it is desirable to have as small an inner diameter as possible, the plane of the receiving drum is at an angle of substantially 30 degrees to the direction taken by the film on leaving the driving mechanism 22, and this angle of inclination requires the arrangement of pulleys carried by the framework 33 described above, and the function of the spiral chute 76' is to turn the film from one direction to the other without cramping or buckling the film.

When the reel of film has been run-through the projecting machine and wound inside of the hollow drum, I find it advisable to insert in the wound film a resilient core or support to hold it in position, and this may be simply effected by placing therein a coiled strip of thin sheet steel as shown at 99 in Fig. 1. This sheet steel is preferably slightly

wider than the film so that when clamped between the side plates 100 of the supply reel or magazine, the film will be held centrally in the mechanism. A stud 101 is supported by the framework 34 to carry the magazine or supply roll. The wound film in the hollow drum may be removed therefrom and placed in the magazine by releasing the locking bolt 46, separating the members of the hollow drum 37 from each other and then removing the wound film from the hollow drum, which operation is done after removing the hollow drum and its contents from the framework 33. The film with its expansible core is then mounted in the supply reel as described and is at once ready for use without an intermediate rewinding operation; since the starting end of the film is the outermost and ready to be threaded through the projector.

To provide that the film shall certainly build up without lateral displacement in the hollow drum, the framework 33 is provided with brackets 102 and 103, which serve to support the conical rollers 104 and 105 respectively, which rollers are proportioned on pitched lines so that they will roll without slipping upon the edge of the convolutions of film if necessary to prevent the film from projecting outside of the hollow drum. I find that the film has practically no tendency to lateral displacement unless there are kinks in the film itself or bad splices between different sections of the film which throw these sections out of alignment with each other.

Fig. 13 shows diagrammatically the course of the film from the supply roll 35 around the driving sprocket 24 and through the loop 28 to the driving sprocket 23 and from thence around the guide roller 76 and through the spiral turn 76^a under the feeding sprocket 74 to the inner surface of the receiving coil 37^a in the hollow drum 37. It will be observed that the limiting internal diameter of the coil 37^a is determined by the size of the spiral chute 76' and feeding sprocket 74, these being the only parts which project into the coil wound in the hollow drum.

The friction driving mechanism consisting of the disk 67 and the pulley 68 is provided so that the pulley 68 may be driven at a rate slightly greater than that corresponding to the linear travel of the film delivered by the sprocket 23 as a result of which there is a small amount of slip between the disk 67 and the pulley 68 which keeps the film between the sprocket 23 and the feeding sprocket 74, tight at all times and thus maintains the film in proper engagement with the sprockets 23 and 74.

From the foregoing description it will be understood that the first end of the film is fed into the hollow drum at the beginning

- of the winding operation, and that as the film is built up in the hollow drum, the feeding mechanism and parts rigidly associated therewith are raised an amount depending 5 upon the thickness of coil wound into the drum; furthermore the feeding mechanism is at all times maintained in proper feeding relation to the wound coil, partly by the weight of the lay-block and parts carried 10 thereby and partly by the downward thrust exerted upon the lay-block by the driving belt.

It will be understood that the feeding roller 15 74 is provided with driving teeth for engaging corresponding holes in the edges of the film for the reason that in many cases the film is not uniformly flat but is distorted and means are required in the feeding mechanism to prevent similar distortion 20 in the wound coil. In cases however, where the film is flat and true I find that the driving teeth may be omitted and a plain feeding roller may be used. My invention may therefore be used to wind strip 25 material which is flat and uniform by means of a plain feeding roller instead of a roller having teeth as shown.

While I have shown my invention in the particular embodiment herein described, I 30 do not, however, limit myself to the construction shown as I may employ any equivalent mechanism that will accomplish the results described.

What I claim is:

35 1. In a film winding mechanism, the combination of a hollow drum, devices rotatably supporting said drum, friction mechanism tending to prevent rotation of said drum, and devices for feeding a strip of 40 film into said drum and rotating the latter against said frictional resistance, said drum, consisting of two semi-circular parts movable from each other to release the coil of film wound therein.

45 2. In a film winding mechanism, the combination of a hollow rotary receptacle, and mechanism for feeding a strip of film into said receptacle whereby a coil of film is wound in said receptacle, said receptacle 50 consisting of two semi-circular parts movable from each other to release the coil of film wound therein.

3. In a film winding mechanism, the combination of a hollow drum, devices for rotatably supporting said drum, friction mechanism tending to prevent rotation of said drum, devices for feeding a strip of film into said drum and rotating the latter against said frictional resistance, said drum 55 consisting of two semi-circular parts movable from each other to release the coil of film wound therein, and locking devices for holding the parts of the drum together in proper relation to receive the film.

60 4. In a film winding mechanism, the com-

bination of a hollow rotary receptacle, and mechanism for feeding a strip of film into said receptacle whereby a coil of film is wound in said receptacle, said receptacle consisting of two semi-circular parts movable from each other to release the coil of film wound therein, and locking devices for holding the parts of the drum together in proper relation to receive the film.

5. In a film winding mechanism, the combination of a hollow drum, devices rotatably supporting said drum, friction mechanism tending to prevent rotation of said drum, devices for feeding a strip of film into said drum and rotating the latter against said frictional resistance, a movable support for said feeding devices to permit the latter to assume different positions corresponding to the inner diameter of the coil of film formed thereby, and driving gearing for said feeding devices for operating said devices at the same rate for the different positions of said movable support, the thrust of said driving gearing upon said feeding devices tending to hold the latter in engagement 90 with the film wound in said drum.

6. In a film winding mechanism, the combination of a hollow rotary receptacle, and mechanism for feeding a strip of film into said receptacle whereby a coil of film is wound in said receptacle, a movable support for said feeding mechanism to permit the latter to assume different positions corresponding to the inner diameter of the coil of film formed thereby, and driving gearing 100 for said feeding mechanism for operating said mechanism at the same rate for the different positions of said movable support, the thrust of said driving gearing upon said feeding mechanism tending to hold the latter in engagement with the film wound in said receptacle.

7. In a film winding mechanism, the combination of a hollow drum, devices rotatably supporting said drum, friction mechanism tending to prevent rotation of said drum, devices for feeding a strip of film into said drum and rotating the latter against said frictional resistance, a movable support for said feeding devices to permit the latter to 110 assume different positions corresponding to the inner diameter of the coil of film formed thereby, driving gearing for said feeding devices for operating said devices at the same rate for the different positions of said 120 movable support, the thrust of said driving gearing upon said feeding devices tending to hold the latter in engagement with the film wound in said drum, and devices for preventing back rotation of the feeding devices whereby back rotation of the driving gearing removes the feeding devices from engagement with the coil of film wound in said drum.

8. In a film winding mechanism, the com-

6
bination of a hollow rotary receptacle, and mechanism for feeding a strip of film into said receptacle whereby a coil of film is wound in said receptacle, a movable support 5 for said feeding mechanism to permit the latter to assume the different positions corresponding to the inner diameter of the coil of film formed thereby, driving gearing for said feeding mechanism for operating said 10 mechanism at the same rate for the different positions of said movable support, the thrust of said driving gearing upon said feeding mechanism tending to hold the latter in engagement with the film wound in said receptacle, and devices for preventing back 15 rotation of the feeding mechanism whereby back rotation of the driving gearing removes the feeding mechanism from engagement with the coil of the film wound in the 20 receptacle.

9. In a film winding mechanism, the combination of means for imparting motion to a strip of film in a first direction, a hollow rotary receptacle for the film located in a 25 plane inclined to said first direction, devices for changing the direction of motion of said film into the plane of said receptacle, mechanism for feeding the strip of film in its changed direction into said receptacle and 30 building up a coil of film in said receptacle, a movable support for the feeding mechanism and direction changing devices permitting the feeding mechanism to assume different positions determined by the amount 35 of film wound in said receptacle, and driving gearing for said feeding mechanism for operating said mechanism at the same rate for the different positions of said movable support, the thrust of said driving gearing 40 upon said feeding mechanism tending to hold the latter in engagement with the film wound in said receptacle.

10. In a film winding mechanism, the combination of means for imparting motion to a strip of film in a first direction, a hollow 45 rotary receptacle for the film located in a plane inclined to said first direction, devices for changing the direction of motion of said film into the plane of said receptacle, mechanism for feeding the strip of film in its changed direction into said receptacle and 50 building up a coil of film in said receptacle, a movable support for the feeding mechanism and direction changing devices permitting 55 the feeding mechanism to assume different positions determined by the amount of film wound in said receptacle, and driving gearing for said feeding mechanism for operating said mechanism at the same rate for the 60 different positions of said movable support, the thrust of said driving gearing upon said feeding mechanism tending to hold the latter in engagement with the film wound in said receptacle, and devices for preventing back 65 rotation of the feeding mechanism

whereby back rotation of the driving gearing removes the feeding mechanism from engagement with the coil of film wound in the receptacle.

11. In a film winding mechanism, the 70 combination of a hollow drum, devices rotatably supporting said drum, friction mechanism tending to prevent rotation of said drum, devices for feeding a strip of film into said drum and rotating the latter against 75 said frictional resistance, a first framework for supporting said drum, a second framework for supporting said feeding devices, said first framework being readily removable from said second framework to remove 80 the coiled film from said drum, mechanism carried by said second framework for holding said feeding devices away from said drum, and tripping devices actuated by placing said first framework in position upon said second framework for moving said holding mechanism to its releasing position. 85

12. In a film winding mechanism, the combination of a hollow rotary receptacle, mechanism for feeding a strip of film into 90 said receptacle whereby a coil of film is wound in said receptacle, a first framework for supporting said receptacle, a second framework for supporting said feeding mechanism, said first framework being 95 readily removable from said second framework to remove the coiled film from said receptacle, mechanism carried by said second framework for holding said feeding mechanism away from said receptacle, and tripping devices actuated by placing said first framework in position upon said second framework for moving said holding mechanism to its releasing position. 100

13. In a film winding mechanism, the 105 combination of means for imparting motion to a strip of film in a first direction, a hollow rotary receptacle for the film located in a plane inclined to said first direction, devices 110 for changing the direction of motion of said film into the plane of said receptacle, mechanism for feeding the strip of film in its changed direction into said receptacle and building up a coil of film in said receptacle, a first framework for supporting said receptacle, a second framework for supporting said feeding mechanism and direction changing devices, said first framework being 115 readily removable from said second framework to remove the coiled film from said receptacle, mechanism carried by said second framework for holding said feeding mechanism away from said receptacle, and tripping devices actuated by placing said first framework in position upon said second framework for moving said holding mechanism to its releasing position. 120

14. In a film winding mechanism, the combination of a hollow drum, devices rotatably supporting said drum, friction mech- 125

- anism tending to prevent rotation of said drum, devices for feeding a strip of film into said drum and rotating the latter against said frictional resistance, a first framework 5 for supporting said drum, a second framework for supporting said feeding devices, said first framework being readily removable from said second framework to remove the coiled film from said drum, mechanism 10 carried by said second framework for holding said feeding devices away from said drum, tripping devices actuated by placing said first framework in position upon said second framework for moving said holding 15 mechanism to its releasing position, a member for supporting the end of a strip of film in engagement with said feeding devices, and connections between said member and said tripping devices for removing said 20 member from its supporting position when said tripping devices are actuated.
15. In a film winding mechanism, the combination of a hollow rotary receptacle, and mechanism for feeding a strip of film 25 into said receptacle whereby a coil of film is wound in said receptacle, a first framework for supporting said receptacle, a second framework for supporting said feeding mechanism, said first framework being 30 readily removable from said second framework to remove the coiled film from said receptacle, mechanism carried by said second framework for holding said feeding mechanism away from said receptacle, tripping 35 devices actuated by placing said first framework in position upon said second framework for moving said holding mechanism to its releasing position, a member for supporting the end of a strip of film in engagement 40 with said feeding mechanism, and connections between said member and said tripping devices for removing said member from its supporting position when said tripping devices are actuated.
45. 16. In a film winding mechanism, the combination of means for imparting motion to a strip of film in a first direction, a hollow rotary receptacle for the film located in a plane inclined to said first direction, devices 50 for changing the direction of motion of said film into the plane of said receptacle, mechanism for feeding the strip of film in its changed direction into said receptacle and building up a coil of film in said receptacle, 55 a first framework for supporting said receptacle, a second framework for supporting said feeding mechanism and direction changing devices, said first framework being readily removable from said second framework 60 to remove the coiled film from said receptacle, mechanism carried by said second framework for holding said feeding mechanism away from said receptacle, tripping devices actuated by placing said first framework 65 for moving said holding mechanism to its releasing position, a member for supporting the end of a strip of film in engagement with said feeding mechanism, and connections between said member and said tripping devices for removing said member from its supporting position when said tripping devices are actuated.
17. In a film winding mechanism, the combination of a hollow drum, devices rotatably supporting said drum, friction mechanism tending to prevent rotation of said drum, devices for feeding a strip of film into said drum and rotating the latter against said frictional resistance, a guard roll for 70 preventing lateral displacement of the coil of film wound in the drum, a movable support for the feeding devices to permit the latter to assume different positions corresponding to the inner diameter of the coil 75 of film formed thereby, driving gearing for said feeding devices for operating the latter at the same rate for the different positions of said movable support, said driving gearing including a friction element tending to 80 drive said feeding devices at a rate in excess of the rate at which the film is supplied to said feeding devices, the thrust of said driving gearing upon said feeding devices tending to hold the latter in engagement with 85 the film wound in said drum, devices for preventing back rotation of the feeding devices whereby back rotation of the driving gearing removes the feeding devices from engagement with the coil of film wound in the 90 drum, and stripping mechanism engaging the wound film near the feeding devices for positively removing the film from the feeding devices and preventing buckling of the 95 coiled film.
18. In a film winding mechanism, the combination of a hollow drum, devices rotatably supporting said drum, friction mechanism tending to prevent rotation of said drum, devices for feeding a strip of film into 100 said drum and rotating the latter against said frictional resistance, a guard roll for preventing lateral displacement of the coil of film wound in the drum, a movable support for the feeding devices to permit the 105 latter to assume different positions corresponding to the inner diameter of the coil of film formed thereby, driving gearing for said feeding devices for operating the latter at the same rate for the different positions 110 of said movable support, said driving gearing including a friction element tending to drive said feeding devices at a rate in excess of the rate at which the film is supplied to said feeding devices, the thrust of said 115 driving gearing upon said feeding devices tending to hold the latter in engagement with the film wound in said drum, devices 120
- 125

for preventing back rotation of the feeding devices whereby back rotation of the driving gearing removes the feeding devices from engagement with the coil of film wound in the drum, stripping mechanism engaging the wound film near the feeding devices for positively removing the film from the feeding devices and preventing buckling of the coiled film, a first framework for supporting said drum, a second framework for supporting said feeding devices, said first framework being readily removable from said second framework to remove the coiled film from said drum, vertical guides carried by said second framework for said movable support, mechanism carried by said second framework for holding said feeding devices away from said drum, tripping devices actuated by placing said first framework in position upon said second framework for moving said holding mechanism to its releasing position, a member for supporting the end of a strip of film in engagement with said feeding devices, and connections between said member and said tripping devices for removing said member from its supporting position when said tripping devices are actuated.

19. In a film winding mechanism, the combination of means for imparting motion to a strip of film in a first direction, a rotary drum for receiving the film located in a plane inclined to said first direction, devices for changing the direction of motion of said film into the plane of said drum, friction mechanism tending to prevent rotation of said drum, mechanism for feeding the strip of film in its changed direction into said drum and building up a coil of film in said drum by rotating said drum against said frictional resistance, a guard roll for preventing lateral displacement of the coil of film wound in the drum, a movable support for the feeding mechanism and direction changing devices permitting the feeding mechanism to assume different positions determined by the amount of film wound in said drum, driving gearing for said feeding mechanism for operating said mechanism at the same rate for the different positions of said movable support, said driving gearing including a friction element tending to drive said feeding mechanism at a rate in excess of the rate at which the film is supplied to said feeding mechanism, the thrust of said driving gearing upon said feeding mechanism tending to hold the latter in engagement with the film wound in said drum, stripping mechanism engaging the wound film near the feeding mechanism and preventing buckling of the coiled film, a first framework for supporting said drum, a second framework for supporting said feeding mechanism and direction changing devices, said first framework being readily removable from said second framework to remove the coiled film from said drum, vertical guides carried by said second framework for said movable support, mechanism carried by said second framework for holding said feeding mechanism away from said drum, tripping devices actuated by placing said first framework in position upon said second framework for moving said holding mechanism to its releasing position, a member for supporting the end of a strip of film in engagement with said feeding mechanism, and connections between said member and said tripping devices for removing said member from its supporting position when said tripping devices are actuated.

mechanism and preventing buckling of the coiled film.

20. In a film winding mechanism, the combination of means for imparting motion to a strip of film in a first direction, a rotary drum for receiving the film located in a plane inclined to said first direction, devices for changing the direction of motion of said film into the plane of said drum, friction mechanism tending to prevent rotation of said drum, mechanism for feeding the strip of film in its changed direction into said drum and building up a coil of film in said drum by rotating said drum against said frictional resistance, a guard roll for preventing lateral displacement of the coil of film wound in the drum, a movable support for the feeding mechanism and direction changing devices permitting the feeding mechanism to assume different positions determined by the amount of film wound in said drum, driving gearing for said feeding mechanism for operating said mechanism at the same rate for the different positions of said movable support, said driving gearing including a friction element tending to drive said feeding mechanism at a rate in excess of the rate at which the film is supplied to said feeding mechanism, the thrust of said driving gearing upon said feeding mechanism tending to hold the latter in engagement with the film wound in said drum, devices for preventing back rotation of the feeding mechanism whereby back rotation of the driving gearing removes the feeding mechanism from engagement with the coil of film wound in the drum, and stripping mechanism engaging the wound film near the feeding mechanism and preventing buckling of the coiled film, a first framework for supporting said drum, a second framework for supporting said feeding mechanism and direction changing devices, said first framework being readily removable from said second framework to remove the coiled film from said drum, vertical guides carried by said second framework for said movable support, mechanism carried by said second framework for holding said feeding mechanism away from said drum, tripping devices actuated by placing said first framework in position upon said second framework for moving said holding mechanism to its releasing position, a member for supporting the end of a strip of film in engagement with said feeding mechanism, and connections between said member and said tripping devices for removing said member from its supporting position when said tripping devices are actuated.

In witness whereof, I hereunto subscribe my name this 20th day of November, A. D. 1915.

DAVID E. GRAY.
